UNITED STATES PATENT OFFICE.

ELEUTHERE PAUL DU PONT, OF MONTCHANIN, DELAWARE.

ROTARY VALVE FOR INTERNAL-COMBUSTION ENGINES.

1,038,319.

Specification of Letters Patent. Patented Sept. 10, 1912.

Application filed May 13, 1910. Serial No. 561,038.

To all whom it may concern:

Be it known that I, ELEUTHERE PAUL DU PONT, a citizen of the United States, residing at Montchanin, county of Newcastle, 5 and State of Delaware, have invented a new and useful Improvement in Rotary Valves for Internal-Combustion Engines, of which the following is a full, clear, and exact description, reference being had to the accompanying drawings, which form a part of 10 this specification.

The object of my invention is to provide a construction permitting the employment of a rotary valve, with all the known advantages incident thereto, and in which leakage is entirely obviated.

The invention consists of a peculiar construction and arrangement of valve and valve casing, together with means for operating the valve in unison with the cylinder piston, as hereinafter described and as pointed out specifically in the claims.

In the drawings: Figure 1 is a general view partly in section. Fig. 2 is an enlarged longitudinal section through the valve chamber on the lines 2—2 of Fig. 3. Fig. 3 is a top view partly broken away. Figs. 4 and 5 are sections on the lines 4—4 and 5—5 respectively of Fig. 3. Fig. 6 is a longitudinal section through the valve chamber in a modified form of my invention. Fig. 7 is a section on the line 7—7 of Fig. 6. Fig. 8 is a view similar to Fig. 6, of still another modification. Fig. 9 is a section on the line 9—9 of Fig. 8. Fig. 10 is a perspective view of the valve and valve actuating mechanism shown in Fig. 8.

a is the cylinder, *b* the reciprocable piston therein connected by crank *c* with the 40 crank shaft *d* turning in bearings in the cylinder casing.

e is a valve casing mounted on the cylinder, and *f* a rotatable valve shaft extending through the valve casing but held from 45 longitudinal movement therein. The valve shaft is driven from the crank shaft by means of a pinion *g* on the crank shaft, a pinion *h* on the valve shaft, and an intermediate counter-shaft *i* carrying pinions *h* and *j* meshing respectively with pinions *g* and *k*, the counter shaft *i* turning in bearings in 50 brackets *l*, *l*, on the cylinder casing.

Feathered on the valve-shaft *f* is a valve composed of two members *m* and *n* connected by a neck *o*, of which *m* is the valve proper and *n* is the valve-head that coöper-

ates with means on the valve casing to shift the valve longitudinally at proper intervals. The valve-shifting contrivance comprises an endless peripheral groove *p* in the valve-head and a plug *q* threaded in the wall of the cylinder and carrying a pin *r* engaging the groove *p*. The groove *p* extends around the valve-head in a plane at right angles to the valve axis for a distance somewhat less than a complete circumference, thence in a direction oblique to the axis of the valve, thence in another plane at right angles to the valve axis for a distance somewhat less than a complete circumference, and thence returns obliquely to the assumed point of beginning of the groove; the two oblique extensions of the groove intersecting. It will be understood that this arrangement causes the valve to rotate in one plane for the greater part of one complete rotation of the crank shaft or one complete reciprocation back and forth of the piston, then to shift longitudinally on its shaft in one direction, then to rotate in another plane for the greater part of one complete rotation of the crank shaft, and then to shift longitudinally in the opposite direction.

Opening through opposite walls of the valve-casing, opposite the valve member *m*, are supply port *x* and exhaust port *y*.

z is a port connecting the valve-casing and the cylinder casing and located in such position that it is open in one longitudinal position of the valve and closed by the valve-head *n* in the other longitudinal position of the valve.

The valve member *m*, from near its outer end to its inner end, is cut away on one side for a distance substantially equal to, or slightly less than, the distance between the inlet and exhaust ports. It is also preferably recessed between its periphery and its hub at opposite sides of its cut-away portion.

The valve-head *n* between its outer or grooved end and its inner end, is provided with two packing rings *s* and *t*, so located and so spaced apart that, when the valve moves into position to close the cylinder port *z*, these rings will extend on opposite sides of the port and effectually seal the same from communication with inlet and exhaust.

The inner wall of the valve casing, opposite the cylinder port *z*, and for a distance equal to the width of that port, is provided

with an eccentrically-shaped groove, as may be best seen in Fig. 5, the deepest part of the groove being adjacent to the port z . This permits a free exhaust of the fluid as soon as the valve, in its longitudinal movement, commences to uncover the port z .

It will be understood that at each rotation of the valve its interior communicates alternately with the intake and the exhaust, but that communication between the intake and exhaust and the cylinder port is cut off at alternate revolutions of the valve by the sliding of the latter in its casing as hereinbefore described. It will therefore be clear that the cycle of operations is as follows: The valve shifts to the right (Figs. 1 and 3) and the valve connects the piston cylinder with the exhaust while the piston is moving up, permitting the dead fluid to exhaust from the cylinder; then the valve in its continued rotation closes the exhaust and connects the piston cylinder with the inlet while the piston is moving down, thereby permitting live motive fluid to enter the cylinder; and then the valve shifts to the left (Figs. 1 and 3), sealing the cylinder port z during the next rotation of the valve and during the next upward compression stroke and the next downward power stroke of the piston.

It will be observed, as characteristic features of the invention, that the interior of the valve is substantially at all times in communication with either the inlet or the exhaust, but that such condition is ineffective to connect the cylinder with either the inlet or exhaust while the valve is shifted to the left or during the compression and power strokes of the piston; and that the foregoing construction lends itself admirably to an arrangement of packing rings whereby the cylinder port is effectually closed with a gas-tight seal during the compression and explosion cycles of the engine.

While only a single cylinder is shown, it is obvious that, in the application of the invention to, for example, an automobile, a plurality of cylinders will be employed.

In the modification shown in Figs. 6 and 7, the valve is shown as geared to the crank-shaft in the relation of one to two; that is, the valve rotates once for each two revolutions of the crank shaft. To effect this, the gear j' immediately engaging the gear k' on the valve is shown as one-half the diameter of the latter. f' represents the valve-shaft, m', o', n' the valve; e' the valve casing; p' the cam groove in the valve member n' ; q', r' , the device fixed on the valve casing and engaging the groove p' ; s', t' , the packing rings; x' the supply port in the valve casing; y' the exhaust port in the valve casing; and z' the port connecting the valve chamber and the cylinder. The only essential particulars in which this modification differs from the form shown in Figs.

1-5 are the arrangement of the supply and exhaust ports, the sectional contour of the valve member m , and the shape of the cam groove. The supply and exhaust ports in the modification are arranged at an angle of 90 degrees from each other instead of diametrically opposite to each other, and the length of the cut-away part of the valve member m' is correspondingly decreased, the same substantially equaling the distance between the supply and exhaust ports; while the two inclined portions of the cam groove are on opposite sides of the valve instead of on the same side. The last-named feature is of advantage in that it avoids the intersection of oppositely inclined portions of the groove and thereby avoids the liability to excessive wear of the engaging pin. The arrangement of the supply and exhaust ports is such that, during the compression and explosion cycles of the engine, the valve cuts off both ports, and the reciprocatory movement of the valve to close the port z' does not, therefore, perform in and of itself, the function of cutting off communication between the cylinder and the supply and exhaust ports; but it continues to perform the important function of closing the cylinder port with a gas tight seal during the compression and explosion cycles of the engine, the attainment of which result is the main purpose of the invention.

In the modification shown in Figs. 8, 9 and 10, the valve is oscillated instead of continuously rotated in the same direction. e^2 represents the valve casing, m^2, o^2, n^2 the valve; s^2, t^2 , the packing rings; x^2 the supply port in the valve casing; y^2 the exhaust port in the valve casing; and z^2 the port connecting the valve chamber and the cylinder. The arrangement of supply and exhaust ports is the same as in the modification shown in Figs. 6 and 7; that is, they are arranged at an angle of 90 degrees from each other, although they may be separated a considerably lesser or greater angular distance.

The valve is given a combined movement of oscillation and reciprocation by the means, shown clearly in perspective in Fig. 10. j^2 represents a gear corresponding to gear j in the first described form of my invention and k^2 the gear directly driven thereby, the gear k^2 being of twice the diameter of gear j^2 . 11 is a crank on the shaft of gear k^2 . 12 is a pin carried by the crank. 14 is a crank pin on the valve, which is not provided with a separate shaft. Pin 14 carries a sleeve 13 slidable on the crank pin 12. In the rotation of the crank 11, it imparts a movement of reciprocation to the crank pin 14 in the direction of the latter's length, thereby reciprocating the valve. At the same time, an oscillatory movement is imparted to the crank pin 14 and valve, this

being permitted by the sliding of the sleeve 13 back and forth upon the pin 12. The number of degrees through which the valve is oscillated depends upon the relative 5 lengths of the cranks, and these members must be so proportioned as to carry the valve through the proper number of degrees required to enable the alternate opening of the ports x^2 and y^2 to be properly 10 effected.

The valve member m^2 owing to the absence of a separate valve shaft is made entirely hollow from the neck o^2 to near its outer end and the opening therein through 15 which its hollow interior alternately communicates with ports x^2 and y^2 is of a width substantially equal to the minimum distance between these two ports.

It will be understood, from the foregoing 20 description, that at each complete oscillation back and forth of the valve, its interior communicates alternately with the intake and the exhaust, but that communication between these ports and the cylinder port is 25 cut off at alternate oscillations of the valve by the sliding of the latter in its casing; the cycle of operations being, therefore, the same as that described in the description of the operation of the embodiment of my in- 30 vention shown in Figs. 1-5.

The above described embodiments of my invention are intended to be illustrative merely, as it is obvious that the advantages secured thereby can be equally well secured 35 by still other modifications that may suggest themselves to those skilled in the art or which may be dictated by particular conditions that may be encountered in the practical application of my invention to different 40 constructions of engines.

While the stated object of my invention is to eliminate the disadvantages ordinarily incident to the employment of a rotary valve I do not intend, by the use of the term 45 "rotary" or "rotatable" to imply continuous turning of the valve in the same direction, but I intend to include in such term any turning movement (such as the oscillatory movement of the valve of Figs. 8, 9 and 10) 50 as distinguished from a reciprocatory movement.

Having now fully described my invention, what I claim and desire to protect by Letters Patent is:

55 1. In an internal combustion engine, the combination with the cylinder, of a valve casing communicating with the cylinder, a supply port and an exhaust port in the valve casing, a valve in the valve casing, and 60 means to rotate and reciprocate said valve, said valve in one of said movements adapted to alternately open the supply and exhaust ports and in the other of said movements adapted to open and close communication 65 between said ports and the cylinder.

2. In an internal combustion engine, the combination with the cylinder, of a valve casing, a supply port and an exhaust port in the valve casing, a valve in the valve casing, and means to rotate and reciprocate 70 said valve, said valve adapted when rotating in one of its longitudinal positions to alternately open communication between the supply port and the cylinder and the exhaust port and the cylinder, and when rotating in the other of its longitudinal positions to maintain said communications closed.

3. In an internal combustion engine, the combination with the cylinder, of a valve 80 casing communicating with the cylinder, a supply port and an exhaust port in the valve casing, a rotatable valve in the valve casing adapted in its turning movement to alternately open the supply and exhaust 85 ports, and means to rotate the valve and also to slide said valve longitudinally to alternately open and close communication between said ports and the cylinder.

4. In an internal combustion engine, the 90 combination with the cylinder, of a valve casing communicating with the cylinder, a supply port and an exhaust port in the valve casing, means to rotate and reciprocate said valve, said valve in one of its movements 95 adapted to alternately open the supply and exhaust ports and in the other of its movements adapted to open and close communication between said ports and the cylinder, and a packing carried by the valve and adapted to be interposed between the cylinder and the supply and exhaust ports in one of said movements.

5. In an internal combustion engine, the combination with the cylinder, of a valve 105 casing communicating with the cylinder, a supply port and an exhaust port in the valve casing, a rotatable valve in the valve casing adapted in its turning movement to alternately open the supply and exhaust 110 ports, means to rotate the valve and also to slide said valve longitudinally to alternately open and close communication between said ports and the cylinder, and a packing ring, carried by the valve, adapted, in one of the 115 sliding movements of the valve, to be interposed between said ports and the cylinder.

6. In an internal combustion engine, the combination with the cylinder, of a valve casing communicating with the cylinder, a supply port and an exhaust port in the valve casing, a valve in the valve casing adapted to convey motive fluid and waste gases, said valve having communicating openings adapted to communicate respectively with the supply and exhaust ports and with the cylinder, and means to rotate and reciprocate said valve, said valve in one of said movements adapted to register one of said valve openings alternately with the supply 130

port and the exhaust port and in the other of said movements adapted to open and close communication between the other of said valve openings and the cylinder.

- 5 7. In an internal combustion engine, the combination with the cylinder, of a valve casing communicating with the cylinder, a supply port and an exhaust port in the valve casing, a valve in the valve casing adapted 10 to convey motive fluid and waste gases, said valve having communicating openings adapted to communicate respectively with the supply and exhaust ports and with the cylinder, and means to rotate said valve to bring one of said valve openings into register with the supply port and exhaust port alternately and to reciprocate said valve to alternately open and close communication between the other of said valve openings and 15 the cylinder.

- 20 8. In an internal combustion engine, the combination with the cylinder and its piston and the crank shaft connected with the piston, of a valve casing, a valve therein, 25 driving connections between the crank shaft and valve imparting rotation to the latter, means coöperating with said driving means to reciprocate the valve longitudinally, a port between the cylinder and valve casing 30 adapted to be alternately opened and closed in the reciprocation of the valve, and a supply port and an exhaust port in the valve casing adapted to be alternately opened in the rotation of the valve.

- 35 9. In an internal combustion engine, the combination with the cylinder and its piston, of a valve casing, ports in the valve casing communicating respectively with the supply, the exhaust and the cylinder, a 40 rotatable longitudinally movable valve in said casing, said valve being cut away to open communication alternately between the supply port and the cylinder port and the exhaust port and the cylinder port, said 45 valve having a portion adapted, at alternate longitudinal reciprocations of the valve, to close communication between the cylinder port and the supply and exhaust ports, and means to rotate and reciprocate said valve 50 in harmony with the movement of the piston.

- 55 10. In an internal combustion engine, the combination with the piston cylinder, of a valve casing, ports in the valve casing communicating respectively with the supply, the exhaust and the cylinder, a rotatable longitudinally movable valve in said casing comprising a valve member adapted in its rotation to open communication alternately with 60 the supply port and the exhaust port and a member adapted in its reciprocation to alternately open and close the cylinder port, and means to impart to said valve said movements of rotation and reciprocation.

- 65 11. In an internal combustion engine, the

combination with the cylinder, of a valve casing, a port communicating between the cylinder and valve casing, the inner diameter of the latter being enlarged at a point opposite said port, a supply port and an exhaust port in said casing, a rotatable longitudinally movable valve in said casing comprising a valve member adapted in its rotation to maintain communication between the enlarged part of the valve casing and the supply port and the exhaust port alternately and a member adapted in its reciprocation to alternately cover and uncover said enlarged part of the casing, and means to impart to said valve said movements of rotation and reciprocation. 80

12. In an internal combustion chamber, the combination with the cylinder, of a valve casing, a port in the casing opening into the cylinder, the casing being provided with an internal groove at a point opposite said port, the wall of said groove being eccentric relative to the remaining part of the casing wall, a valve in said casing composed of two members and a connecting neck, means to rotate the valve continuously and to move it back and forth, one of said members in one longitudinal position of the valve bridging the said groove and in its other longitudinal position extending to one side of said groove, the other of said members or the valve proper being cut away so as to communicate with said port and groove in the last-named longitudinal position of the valve, and a supply port and an exhaust port in said casing adapted to be alternately opened by the valve in its rotation in either longitudinal position thereof. 100

13. In an internal combustion engine, the combination with the piston cylinder, of a valve casing, ports in the valve casing communicating respectively with the supply, the exhaust and the cylinder, a rotatable longitudinally movable valve in said casing comprising a valve member adapted in its rotation to open communication alternately with the supply port and the exhaust port and a member adapted in its reciprocation to alternately open and close the cylinder port, packing rings surrounding the last-named member adapted in one position of the valve to extend on opposite sides of the cylinder port, and means to impart to the valve said movements of rotation and reciprocation. 110

14. In an internal combustion engine, the combination with the cylinder and its piston and the crank shaft connected with the piston, of a valve casing, a valve therein, driving connections between the crank shaft and valve imparting rotation to the latter, there being an endless groove in said valve parts of which lie in two planes at right angles to the axis of rotation of the valve and the remaining parts of which extend obliquely and connect the first-named parts, a stationary 120 125 130

member in the valve casing engaging said groove, thereby reciprocating the valve longitudinally, a port between the cylinder and valve casing adapted to be alternately 5 opened and closed in the reciprocation of the valve, and a supply port and an exhaust port in the valve casing adapted to be alternately opened in the rotation of the valve.

15. In an internal combustion engine, the 10 combination with the cylinder, of a valve casing, a supply port and an exhaust port in the casing and a port between the cylinder and casing, a valve, means to rotate said valve continuously and to shift it back and 15 forth intermittently, and means comprised in the valve adapted in each rotation to open said supply port and exhaust port alternately and in its reciprocation to open said cylinder port at alternate rotations of the 20 valve.

16. In an internal combustion engine, the 25 combination with the cylinder, of a valve casing communicating with the cylinder, a supply port and an exhaust port in the casing, a valve in the casing, and means to rotate and reciprocate said valve, said valve being composed of two members, one member being located in that part of the valve 30 casing containing the supply and exhaust ports and being cut away to adapt it, in one of said movements of the valve, to alternately open communication between said ports and the interior of the valve casing, the other valve member being located adj- 35 cent to the cylinder port and adapted in the other of said movements of the valve to

alternately open and close communication between the interior of the valve casing and the cylinder.

17. In an internal combustion engine, the 40 combination with the cylinder, of a valve casing communicating with the cylinder at one point only between the ends of the casing, a supply port and an exhaust port toward one end of the casing, a valve in the 45 valve casing, means to rotate and reciprocate said valve, said valve being composed of two members spaced apart, one valve member being located in that part of the valve casing provided with the supply and exhaust ports 50 and being cut away to permit either of said ports to communicate with the space between the members, the other valve member being located at the opposite part of the valve, the first valve member adapted, in the rotary 55 movement of the valve, to alternately open the supply port and exhaust port to said cut-away portion and the second valve member adapted, in the reciprocating movement of the valve to open and close the cylinder 60 port, and packing rings carried by the second valve member near the inner end thereof and adapted, in one position of the valve, to extend on opposite sides of the cylinder 65 port.

In testimony of which invention, I have hereunto set my hand, at Philadelphia, on this 10th day of May, 1910.

ELEUTHERE PAUL DU PONT.
